US00D848812S

(12) **United States Design Patent** (10) **Patent No.:** **US D848,812 S**
Bloch (45) **Date of Patent:** **** May 21, 2019**

(54) **FOLDING KNIFE**

(71) Applicant: **Outdoor Edge Cutlery Corporation**,
Denver, CO (US)

(72) Inventor: **David R. Bloch**, Morrison, CO (US)

(73) Assignee: **OUTDOOR EDGE CUTLERY
CORPORATION**, Denver, CO (US)

(**) Term: **15 Years**

(21) Appl. No.: **29/551,796**

(22) Filed: **Jan. 15, 2016**

(51) LOC (11) Cl. **08-03**

(52) U.S. Cl.

USPC **D8/99**

(58) **Field of Classification Search**

USPC D8/98, 99, 100, 107; D22/118
CPC B26B 1/00; B26B 1/02; B26B 1/04; B26B
5/00; B26B 5/006; B26B 1/10; B26B
1/046

& Smith LLP; Craig W. Mueller

(57) **CLAIM**

The ornamental design for a folding knife, as shown and described.

DESCRIPTION

FIG. 1 is a perspective view of the folding knife;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view showing the blade in a second position of use;

FIG. 9 is a perspective view of an alternate embodiment, the only difference being the lower blade edge is not claimed;

FIG. 10 is a perspective view of an alternate embodiment, the only difference being the lower blade edge includes a serrated portion;

FIG. 11 is a front elevation view thereof;

FIG. 12 is a rear elevation view thereof;

FIG. 13 is a left elevation view thereof;

FIG. 14 is a right elevation view thereof;

FIG. 15 is a top plan view thereof;

FIG. 16 is a bottom plan view thereof; and,

FIG. 17 is a perspective view showing the blade in a second position of use.

The broken lines depict portions of the folding knife in which the design is embodied that form no part of the claimed design.

1 Claim, 11 Drawing Sheets
